UNITED STATES PATENT OFFICE.

PETER PARKE, OF CHICAGO, ILLINOIS, ASSIGNOR TO THE PULLMAN COMPANY, OF CHICAGO, ILLINOIS, A CORPORATION OF ILLINOIS.

WINDOW ARRANGEMENT FOR SLEEPING CARS.

Application filed August 23, 1923. Serial No. 658,970.

To all whom it may concern:

Be it known that I, PETER PARKE, a citizen of the United States, and resident of Chicago, county of Cook, and State of Illinois, have invented certain new and useful Improvements in Window Arrangements for Sleeping Cars, of which the following is a specification, and which are illustrated in the accompanying drawings, forming a part 10 thereof.

This invention relates to railway cars and more particularly to windows for sleeping cars or Pullman sleepers and similar vehicles, and one of the objects of the invention 15 is the provision of new and improved means for ventilating the upper berths of sleeping cars and the like.

Another object of the invention is the provision of windows for the upper berths of 20 sleeping cars for light and observation purposes.

A still further object of the invention is the provision of windows for the upper berths of sleeping cars together with means 25 for protecting said windows against breakage and means whereby said windows may be adjusted to different positions.

Other and further objects and advantages 30 of the invention will appear from the following description taken in connection with the accompanying drawings, in which

Fig. 1 is a side elevation of the interior of a sleeping car, with parts broken away;

Fig. 2 is a vertical section on line 2—2 of 35 Fig. 1;

Fig. 3 is a section on line 3—3 of Fig. 2;

Fig. 4 is a side elevation of a portion of a side wall of the car showing the upper window in position therein;

Fig. 5 is a section on line 5—5 of Fig. 4; 40 and

Figs. 6 and 7 are detail views showing the mounting for the shield.

In the construction of sleeping cars the 45 provision of a window for light and ventilation for the upper berth has heretofore been prevented by the window and screen arrangement for the lower berth. As usually constructed, a pocket is formed 50 above the lower or side window in which the screen is stored when not in use, and the distance between the top of the window when it is raised and the lower deck is such as to render the provision of a window for 55 the upper berth impractical.

These difficulties have been overcome by so arranging the parts that the side window can be elevated only a limited distance and by securing the screen to the lower portion of the window whereby the same is automatically moved to operative position when the window is elevated and to inoperative or stored position in a recess or pocket beneath the window when the latter is lowered or in closed position. 60

Referring now to the drawings in which the same reference characters are employed to indicate similar parts throughout the drawings, the numeral 10 designates a sleeping car or coach provided with the side wall 70 11 comprising the inner and outer walls 12 and 13, respectively. The side plate 14 maintains the upper ends of the walls in spaced relation and separates the side wall 11 from the lower deck 15, all of which is of the 75 usual or well-known construction.

The car is provided with the usual fixed seats 16 for forming the lower berth and the hinged berth support 17 for forming the upper berth, the latter being shown in lowered or operative position in dotted lines in Fig. 2.

The side wall 11 is provided with two side windows 18 which are vertically movable in suitable guides. Each window may, if desired, include two transparent sections 19 and 20 arranged in spaced relation to form an air or insulating space therebetween as shown in Fig. 2. Screens 21 are adapted to be associated with the lower portion of the 90 windows whereby when the windows are elevated the screens will protect the window openings 22 beneath said windows, as shown in Fig. 1.

Suitable means are provided for the upper 95 berth for light and ventilating purposes. As shown, the side wall 11 is provided with an opening 23 which is provided with a transparent closure. The openings 23 are located adjacent to the side plate 14 in order that 100 the spaces below said closures may be sufficiently deep to receive the upper portions of the windows 18 when the same are in elevated position. Preferably each closure includes a double window comprising the 105 transparent members 24 and 25 spaced apart to form an air or insulating space therebetween as shown in Fig. 2.

The transparent closure is preferably mounted in such a manner that it may be 110

moved to a position to permit the entrance of air to the upper berth. In the form of the device selected to illustrate one embodiment of the invention, the opening 23 is provided with a tubular casing 26, of any suitable shape in cross-section, in the outer end of which is telescopically arranged or slidably mounted a corresponding tubular window support 27 in the outer end of which 5 is rigidly secured the transparent member or window 24. The support 27 is provided with suitable ventilator openings 28 which may be protected by the usual wire screen 29. The ventilating openings 28 may be 10 located on any convenient portion of the support 27 but are preferably located on the under side thereof. When the window support 27 with its window 24 is moved laterally outwardly air may enter through ventilator openings 28 into the tubular casing 26. 15

The window 25 is adapted to be moved to a position to permit the entrance of air. For this purpose suitable means are provided whereby said window may be moved to 25 a position to uncover said opening 23. As shown, the window is hinged as at 30 whereby the same may be moved to the open position as shown in dotted lines in Fig. 2. Any suitable means may be provided for holding 30 the window 25 in either the inoperative or open position or in the closed position, such as the spring-pressed ball 31 carried by the free edge of the window which is adapted to engage the recess 32 in the casing 26 to 35 hold the window in closed position, or the recess 33 in the bracket 34, Fig. 1, for holding the window in the open position. A sealing strip 35, Fig. 5, of any suitable material may be provided about the windows 25 to prevent the entrance of cold air 40 in winter and incidentally to prevent rattling of the parts.

Since the window 24 is located outwardly of the interior of the car it is desirable that 45 means be provided for operating the same. Any suitable means may be provided for that purpose. As disclosed, means are provided whereby the window 24 is moved outwardly when the window 25 is moved to its 50 open position. One means for accomplishing this is disclosed in Fig. 2 and will now be described.

The lever 36 is pivotally connected intermediate its ends to a fulcrum member 37 55 secured on the inner side of the tubular casing 26. The lower end of the lever 36 is provided with the pivot or stud 38 which is adapted to engage an elongated slot 39 on the plate 40 carried by the window support 27. A link 41 connects the upper end 60 of the lever 36 with the upper portion of the window 25. It will thus be seen that the parts are so arranged that when the window 25 is moved to the dotted line position 65 shown in Fig. 2 the lever and link connec-

tion between the windows 25 and 24 will cause the window support 27 to be moved outwardly to the dotted line position shown in said figure.

A suitable shield may be provided for 70 protecting the glass of the window 25 and for screening the window opening when it is so desired. As shown, the shield or screen 42 is provided for this purpose. This shield may if desired be formed from sheet metal. 75 It may be, and preferably is, provided with louvers 43 whereby the shield may be employed as a screen to intercept the light without interfering with ventilation when the windows are open. 80

In order to operate the window 25 it is necessary that the shield 42 be movable. Any suitable means may be provided for this purpose. As shown, a guideway member 44 hinged as by means of the hinges 46, 85 Fig. 6, to brackets 45 which are adapted to be attached to the inner wall of the car, is provided for this purpose. The member 44 is provided with a return bend 47 which is adapted to be engaged by a corresponding return bend 48 on the lower end of the shield 42. The hinges 46 are provided with suitable springs 49, Fig. 7, whereby the shield 42 is resiliently held against the inner wall of the car. These springs are so constructed that they hold the shield 42 against the inner side of the car with sufficient force to prevent rattling and accidental movement of the same. The guideway member 44 is extended laterally of the window 25 whereby the shield 42 may be slid along the guideway to a position laterally of said window. 90

I claim as my invention:

1. In a railway car, a vertically movable 105 window in the side wall of said car, an upper window and means for mounting said upper window in said side wall above the movable window for moving the same laterally of said wall.

2. In a sleeping-car having an upper berth, a side wall opposite said berth, said side wall being provided with an opening, and a horizontally movable window for closing said opening.

3. In a sleeping-car having a lower deck and a side wall provided with a ventilator opening a window in said side wall below said opening, and a shield movably mounted to extend across said opening or to be removed therefrom.

4. In a sleeping car provided with an upper berth, a double window for said berth, one of said windows being movable horizontally.

5. In a sleeping car having upper berths, and having its side walls provided with window openings opposite said upper berths, windows for said openings, said windows being movable for ventilating said berths.

and movable shield or guard members for said windows.

6. In combination with a sleeping car having an upper berth, a double window for said upper berth and a shield for said window located inwardly thereof and movable relatively thereto.

7. The combination with a sleeping car having a side wall and a lower deck and provided with an upper berth of means associated with said side wall below said deck and bodily movable in a plane at right angles thereto for permitting the entrance of light and air into said upper berth.

8. In a sleeping car having a side wall provided with an opening therein a bed support hinged to said side wall below said opening, a window having a support telescopically engaging said opening, said support provided with ventilator openings whereby when said window is moved outwardly air may enter through said ventilator openings.

9. In combination with the side wall of a car having an upper and a lower opening therein, and an upper and a lower berth associated therewith, a lower vertically movable window in said lower opening, a movable window in said upper opening, a support for said movable window provided with ventilator openings therein, and means for opening and closing said ventilator openings.

10. In combination with the side wall of a car having an opening therein of a double window for closing said opening, one of said windows having means for slidably engaging said opening, said means being provided with ventilating apertures therein, means adjacent said opening for hinging the other of said windows, means interconnecting said windows whereby when one of them is moved it will operate the other, and a shield for one of said windows.

PETER PARKE.
